UNITED STATES PATENT OFFICE.

THOMAS A. McCALL, OF XENIA, OHIO.

PNEUMATICALLY-OPERATED MASSAGE APPARATUS.

No. 882,532.

Specification of Letters Patent. Patented March 17, 1908.

Application filed May 31, 1906, Serial No. 319,600. Renewed January 15, 1908. Serial No. 410,996.

To all whom it may concern:

Be it known that I, THOMAS A. McCALL, a citizen of the United States, residing at Xenia, in the county of Greene and State of Ohio, have invented certain new and useful Improvements in Pneumatically - Operated Massage Apparatus; and I do hereby declare the following to be a full, clear, and exact description of the invention, such as will enable others skilled in the art to which it app pertains to make and use the same, reference being had to the accompanying drawings, and to the letters and figures of reference marked thereon, which form a part of this specification.

This invention relates to new and useful improvements in pneumatically - operated massage apparatus, and the object of the invention is to produce a device of this nature, whereby a series of rapid vibrations may be imparted through a suitable cup, and also in the provision of means whereby a constant vacuum force may be exerted by connection with a vacuum storage tank.

The invention consists further in various details of construction and combinations and arrangements of parts which will be herein-after fully described and then specifically defined in the appended claims.

I illustrate my invention in the accompanying drawings, which, with the letters of reference marked thereon, form a part of this application, and in which drawings:

Figure 1 is a top plan view of my apparatus, parts being shown in section. Fig. 2 is a vertical sectional view on line x—x of Fig. 1. Fig. 3 is a side elevation, partly in section. Fig. 4 is a detail sectional view through one of the massage cups, and Fig. 5 is a similar sectional view through a modified form of cup.

Reference now being had to the details of the drawings by letter, A designates a casing having a hinged cover A', and mounted within said casing is a standard B supporting a cylinder B', one end of the cylinder having a pipe C communicating therewith, which pipe leads through one end of the casing and has a hollow handle D connected therewith, which handle has a contracted end which is threaded, as at D', and over which the cup E is adapted to be fastened, a detail view of said cup and connection being clearly shown in Fig. 4 of the drawings. It will be noted that a disk d is adapted to rest upon a shoulder formed in said cup and against which the

contracted end of the handle is adapted to bear. Said disk comprises a very fine mesh screen for the purpose of preventing dust or other foreign matter entering the pipe and cylinder. Mounted within said cylinder is a stem G having two pistons H and H', one secured to each end of said piston stem, and J designates a pin fixed centrally to said stem and passing through elongated slots 65 formed at positions diametrically opposite in said cylinder. It will be understood that said pistons move freely within the cylinder, with a sufficient space intervening between the circumferences thereof and the inner 70 surface of the cylinder, so as to allow the air which is drawn into the cylinder through the pipe C, on the inner throw of the piston, to escape on the outward or return throw of the piston adjacent to the pipe C, by said air 75 passing about the circumference of the piston and to the atmosphere through the slots in which the pin J works. The air which is drawn into the cylinder from the chamber N is allowed to escape in the same 80 manner about the piston adjacent to the exit end of the cylinder to which the pipe N' is connected.

K designates a flap valve secured to the inner surface of one end of the cylinder and 85 adapted to close over the opening into the tube or pipe C, and a pipe N' leads from the opposite end of the cylinder and communicates with said chamber N. A pipe M leads from the chamber N through the wall of the 90 casing, and a cup M' is fitted to one end thereof, the end of the cup being provided with a perforated diaphragm O. It will be understood that when an obstruction is placed over the mouth of said cup, no air can 95 be drawn into said chamber N and as the air already contained therein is drawn out through the pipe N', a vacuum will be caused in the chamber.

In the present instance, I have shown a 100 coin controlled apparatus for starting my massage apparatus, which consists of a slide P upon which the coin is placed and which causes the coin, as the plate is pushed upon, to throw a pivotal switch S to close a circuit 105 and start the motor. At a predetermined moment, the circuit may be broken by tilting the lever T which is actuated by a pin upon one of the gear wheels driven by said motor. The motor Q which transmits motion to the gear wheel I to which the pitman J is eccentrically pivoted, is adapted to drive 110

said pitman which has forked ends, the arms of which are connected to the ends of the pin J which project through oppositely disposed slots in the cylinder.

5 The operation of my apparatus will be understood, when taken in connection with the drawings, and is as follows. When it is desired to start the motor, a coin is pushed by the plate P against the switch, causing the 10 same to close the circuit, which will start the apparatus. As the motor operates, the pistons within the cylinder will be actuated, thereby causing a succession of rapid vibrations in one massage cup E, by the valve K 15 closing upon the movement of the piston H toward said valve, and by the opening of the valve upon the movement of the piston in the opposite direction. This movement, it will be noted, alternately closes and opens 20 communication with the vacuum end of the cylinder which causes the rapid vibrations as the cup is held against an object while a constant vacuum force may be obtained from the cup M' which communicates with the 25 vacuum tank M.

The cups may be applied to various parts of the body of a person and the vibrating effect or the effect of the suction imparted to the body of a person.

30 What I claim is:—

1. A pneumatic massage apparatus comprising a casing, a cylinder mounted therein, a piston stem, a plurality of pistons mounted upon said stem, means outside the cylinder 35 for actuating said stem, pipes communicating with the ends of said cylinder, and a suction cup connected to one of said pipes, as set forth.

2. A pneumatic massage apparatus comprising a casing, a cylinder mounted therein, 40 a piston stem, a plurality of pistons mounted upon said stem, means outside the cylinder for actuating said stem, pipes communicating with the ends of said cylinder, a suction cup connected to one of said pipes, a chamber 45 communicating with one of said pipes, and a suction cup with a pipe leading therefrom to said chamber, as set forth.

3. A pneumatic massage apparatus comprising a casing, a cylinder mounted therein, 50 a piston stem mounted within said cylinder, pistons secured to said stem, a valve-regulated pipe opening through one end of the cylinder and through the casing, a suction cup connected to the pipe, a pitman, a pin 55 secured thereto and passing through the wall of the cylinder and connected to said stem, and means for reciprocating said pitman, as set forth.

4. A pneumatic massage apparatus comprising a casing, a cylinder mounted therein, a piston stem mounted within said cylinder, pistons secured to said stem, a valve-regulated pipe opening through one end of the cylinder and through the casing, a hollow 65 handle secured to said pipe, a suction cup secured to the end of said handle, and a screen disk seated upon a shoulder in said cup and against which the handle is adapted to bear, as set forth.

In testimony whereof I hereunto affix my signature in the presence of two witnesses.

THOMAS A. McCALL.
